John A. H. Siers, Jersey City, N. J.

Application November 9, 1934, Serial No. 752,197

7 Claims. (Cl. 135—23)

This invention relates to umbrellas and has for its general object and purpose to provide an umbrella, parasol or the like, having a collapsible frame and staff of such construction as to effect 5 a marked reduction in the overall length of the umbrella when closed, so that it may be conveniently carried in the pocket, handbag or suitcase.

Another object of the invention is to provide 10 an umbrella frame having relatively sliding rib sections, together with positively acting, manually controllable means for actuating the sliding rib sections to radially extend or contract the frame in the opening and closing movements 15 thereof.

An additional object of the invention resides 20 in the provision of a covering of elastic, waterproof material for the frame, attached at its center to the umbrella staff and at its outer edge to the ends of the sliding rib sections, said material, 25 by contraction thereof, facilitating the inward sliding movement of said rib sections.

A more particular object of the invention is 30 to provide stretcher rods, connected with said sliding rib sections and a runner on the umbrella staff, together with link members pivotally connected to the staff and to said stretcher rods intermediate of their ends, and positively operating the latter to distend or contract the umbrella 35 frame, the said parts being so constructed and arranged as to lie in compact parallel relation, closely adjacent to the staff, when the umbrella is closed.

My invention has for a further object to provide 40 an umbrella staff of improved construction, embodying telescoping sections, and simple and effective means for retaining said staff sections in extended or collapsed relation.

I also propose to provide an umbrella or parasol of the above character, the several parts of 45 which are strong and durable, while of comparatively light weight, as well as efficient and reliable in practical use.

With the above and other objects in view, the 50 invention consists in the improved umbrella or parasol, and in the form, construction and relative arrangement of its several parts, as will be hereinafter more fully described, illustrated in the accompanying drawings, and subsequently incorporated in the subjoined claims.

In the drawings, wherein I have illustrated several simple and practical embodiments of the invention, and in which similar reference characters designate corresponding parts throughout 55 the several views.

Figure 1 is a fragmentary vertical section, showing the umbrella open and ready for use.

Fig. 2 is a transverse section on an enlarged scale, taken on the line 2—2 of Fig. 1.

Fig. 3 is a fragmentary vertical section, showing the umbrella closed, with the parts of the frame and staff in collapsed position.

Fig. 4 is a fragmentary horizontal section on an enlarged scale, taken on the line 4—4 of Fig. 3.

Fig. 5 is a sectional view taken on the line 5—5 of Fig. 1.

Fig. 6 is a perspective view showing the umbrella frame open.

Fig. 7 is a similar view of the closed umbrella, the covering being omitted.

Fig. 8 is a sectional view similar to Fig. 3, illustrating a slightly modified construction.

Fig. 9 is a horizontal section on an enlarged scale, taken on the line 9—9 of Fig. 8.

Referring in detail to the drawings, the staff 20 of the umbrella, as herein shown, embodies upper and lower sections, 5 and 6 respectively, of thin-walled metal tubing, said lower section, preferably, being telescoped within the upper section 5. The wall of the latter section, at its lower 25 end, is formed with an internal shoulder 7, to be engaged by a bead 8 on the upper end of the staff section 6 to limit the outward extension thereof from the section 5.

Within the staff section 6 a leaf spring 9 is 30 suitably fixed at one of its ends and normally is slightly bowed longitudinally. The free end of said spring, within the upper end of the section 6, is provided with latching means 10 for a purpose to be later explained. To the convex 35 side of the spring 9 intermediate of its ends, a lug 11 is fixed and projects outwardly through a slot 12 in the wall of the staff section 6. This lug is received in a recess 13 in the lower end 40 of the wall of the staff section 5, to releasably hold the section 6 in its extended position and prevent relative rotational movement of the staff sections. A stud 10' is secured to the spring 9, in spaced relation to the latching means 10, and bears against the wall of the staff section 6.

To the lower end of the staff section 6 a handle member 14 is suitably fixed, said handle member being of tubular form at its upper end to provide the annular wall or flange 15.

Upon the upper end of the staff section 5 a 50 sleeve 16 is threaded. The upper end of this sleeve is closed and formed with a radially projecting slotted flange 17 in which the rib sections 18 are pivoted at one of their ends as at 18'. These rib sections are of channel form in cross 55

section, and are preferably provided along the inwardly facing open sides of the channels with the opposing, longitudinally continuous flanges 19.

In each rib section 18 a longitudinally slidable 5 rib section 20 is telescopically engaged. The sections 20 are also of channel form and are retained and guided for free sliding movement within the sections 18 by the flanges 19 of the latter.

To each rib section 20 a stretcher rod 21 is 10 connected at one end. This stretcher is likewise preferably of channel form and a plate 22 in the channel thereof has its ends pivotally connected, as at 23, with the side walls of the channel. This plate is centrally formed with an inverted U-shaped portion 24 which extends into the channel of the rib section 20 and has openings in the sides thereof to receive inwardly projecting parts of the side walls of said rib section, as shown at 24'. However, any other desired means may be 15 utilized for pivotally connecting the stretcher rods to the sliding rib sections 20.

On the staff section 5 a runner 25 is slidably engaged. The inner ends of the stretchers 21 are curved, as at 26, and pivotally connected to a 20 slotted flange formed on the upper end of the runner 25, as shown at 27. Upward movement of the runner is limited by a collar 28 fixed on the staff section 5, and the wall of said section is provided with an opening 29 to receive the 25 end of a spring pressed latch member 30 mounted on the runner, whereby the latter is releasably held against downward movement.

Links 31 are pivotally connected at one of their ends to a slotted flange on the lower end of the sleeve 16, as at 32, and have their other ends pivotally connected at 33 to the stretcher rods 21, intermediate the ends of the latter.

The rib sections 18 and 20 are covered with a 30 sheet of rubberized fabric or other elastic textile material, indicated at 34. At its center this elastic covering material is securely fixed to the closed upper end of the sleeve 16 by the clamping plate 35 and screw 36 which is threaded in the end of the sleeve. At its inner end this screw is formed with a reduced neck 37 and conical terminal 38, which provides an annular shoulder 39 to be engaged by the latching means 10 of the spring 9. This latch means for the staff sections is not herein claimed, as it forms the 40 subject-matter of my co-pending application for patent, Serial No. 52,049, filed November 29, 1935.

To the outer edge of the cover 34, at suitably spaced points, appropriate means, such as the tubular members 40, are attached. These members receive the outer ends of the respective rib sections 20 and are securely fixed thereon.

To the underside of each rib section 18 at its outer end a spring clip 41 is suitably fixed, and has an outwardly projecting yieldable finger 42, spaced from the rib section, to be engaged by the flange 15 of the handle 14, as clearly shown in Fig. 3 of the drawings.

When the umbrella is open, as shown in Fig. 1, the covering material 34 is radially and circumferentially expanded or stretched by the extension of the rib sections 20. To close the umbrella the latch 30 is released with one hand while with the other the lug 11 is pushed inwardly and staff section 6 moved upwardly a short distance into the section 5. The runner 25 is now moved downwardly so that the links 31, aided by the contraction of the covering material 34, will operate the stretcher rods 21 to cause the rib sections 20 to slide inwardly on the rib sections 18. When 75 fully closed the latter rib sections are received

within the channels of the stretchers 21, which, together with the links 31, lie in close parallel relation to the staff section 5. The staff section 6 is then moved into the section 5 until its end abuts against the end wall of the sleeve 16, at 5 which time the terminal means 10 of the spring 9 snaps over the shoulder 39 of screw 36. Stud 10', bearing against the wall of staff section 6, assures adequate tension in the spring to resist unintentional outward movement of said staff 10 section. The end of staff section 5 is received in the tubular end of the handle 14, and flange 15 is engaged over the spring fingers 42, to retain the relatively foldable parts in closely associated relation, as shown in Fig. 3. The elastic quality 15 of the cover material 34 is such as to still maintain a certain tensional pull upon the rib sections 20 after the umbrella is closed, while the loose foldable portions of the cover between the circumferentially spaced ribs is reduced to a mini- 20 mum.

In opening the umbrella the staff section 6 is first extended from the section 5. Upon the release of the fingers 42 a slight radial outward movement of the ribs and stretchers will occur. 25 The runner 25 is then moved upwardly on the staff section 5. By reason of the curved ends 26 of the stretchers the upward thrust will be transmitted in a radially outward direction to cause a relative pivotal movement between said stretchers and the rib sections 18. Simultaneously the links 31 exert an outward thrust upon the stretchers to automatically move the other ends thereof longitudinally of the rib sections 18, and thus 30 radially project the rib sections 20, until the runner reaches the limit of its upward movement and latch member 30 is engaged in the opening 29 of staff section 5. The links 31 are preferably so arranged that they are at all times substantially parallel to the rib sections 18. Due to the 40 angular relation of the stretchers 21 and links 31, the telescopic ribs are strongly braced and the expanded covering material held under tension in smooth close contact upon said ribs.

In Figs. 8 and 9 of the drawings I have illustrated a slight modification in which the arrangement of the stretcher rods is reversed with respect to that shown in Figs. 1 and 3. Thus, these stretchers 21' have curved outer ends 26' connected to the sliding rib sections 20, and the 50 channels of said stretchers open inwardly instead of outwardly. Therefore, when closed, said channels receive the links 31. This arrangement obviates the possibility of the cover material being caught between the edges of the side flanges 55 of the stretchers and the rib sections 18 and cut or damaged. This form of the invention operates in the same manner as that first described.

From the foregoing it will be seen that I have 60 devised an improved umbrella or parasol, which, when closed, is of materially reduced overall length so that it may conveniently be carried in a hand bag, suit case or overcoat pocket. At the same time excessive folding of the cover material is avoided and a more compact relationship of the several parts obtained than in similar devices heretofore suggested, thus materially reducing bulk and minimizing the possibility of damage to the cover. The several parts of the 70 umbrella frame may be readily fabricated from light sheet metal stock. However, these parts, being of channel shaped form, are very strong and durable, offering maximum resistance to distorting or bending stresses. 75

While the embodiments of my invention herein disclosed are very efficient in operation and well adapted for practical manufacture at comparatively low cost, it will nevertheless be understood, 5 that the essentially novel features thereof are susceptible of production in various other alternative structural forms. Therefore, the privilege is reserved of resorting to all such legitimate changes in the form, construction and relative arrangement of the several elements as may be fairly comprehended within the spirit and scope of the appended claims.

I claim:

1. In combination with an umbrella having a staff and a runner thereon; a frame comprising telescopically connected inner and outer rib sections, said inner sections being pivotally connected to the staff, and means operable in the movement of said runner to open or close the frame and positively extend or retract the outer rib sections relative to the inner sections, said means including channel-shaped stretchers pivotally connected to the runner and to said outer rib sections and rigid means pivotally connected to the stretchers and to said staff, the pivoted end of each inner rib section and the pivotal connection between said rib section and the associated stretcher, being disposed in substantial alignment with the axis of the rib section, said inner rib sections being disposed in parallel relation to the stretchers throughout the length of the latter and within the channels of said stretchers across the major portion of their width when the frame is closed.
2. In combination with an umbrella having a staff and a runner thereon; a frame comprising telescopically connected inner and outer rib sections, said inner sections being pivotally connected to the staff, and means operable in the movement of said runner to open or close the frame and positively extend or retract the outer rib sections relative to the inner sections, said means including channel-shaped stretchers pivotally connected to the runner and to said outer rib sections and rigid means pivotally connected to the stretchers and to said staff, said rigid means being disposed throughout the length thereof in parallel relation to the stretchers and within the channels of said stretchers when the frame is closed.
3. In combination with an umbrella frame having telescoping ribs and means for positively extending and contracting said ribs; a covering on said ribs of woven rubberized fabric, expanding and contracting radially of said frame in the operation of said means.
4. In combination with an umbrella having a staff, ribs each comprising an inner section, pivotally connected to the staff, and an outer section 10 slideable on said inner section operating means

for the latter rib sections including a runner on the staff; a covering of woven rubberized fabric secured to the staff and to the outer ends of said slideable rib sections, said covering expanding and contracting radially of said frame in the 5 operation of said runner, and being under radial tension along the ribs when the frame is closed, whereby the slideable rib sections are urged inwardly on the inner rib sections in the contracted condition of the covering.

5. In combination with an umbrella having a staff, ribs each comprising an inner section, pivotally connected to the staff, and an outer section 15 slideable on said inner section, operating means for the latter rib sections including a runner on the staff; a covering of elastic textile material secured at its center to the staff, unattached to the inner rib sections, and attached only at its outer edge to the slideable rib sections, said covering expanding and contracting radially of said frame 20 in the operation of said runner, and being under radial tension along the ribs when the frame is closed, whereby the slideable rib sections are urged inwardly on the inner rib sections in the contracted condition of the covering.

6. In combination with an umbrella staff having a runner thereon; a frame comprising inner rib sections, pivotally connected to the staff, and outer rib sections longitudinally extensible with respect to the inner sections, a stretcher pivotally connected to each extensible rib section and to said runner, the pivoted end of each inner rib section and the pivotal connection between said rib section and the associated stretcher, being disposed in substantial alignment with the axis 30 of the rib section, a link pivoted at one end to the staff and at its other end to the stretcher operating to extend and retract the extensible rib section in the operation of the runner, one of said parts being of channel-s' aped form in cross section and the other part, throughout its length, extending in parallel relation to said channel-shaped part and within the channel thereof for the major portion of its width when the umbrella 35 frame is closed.

7. In combination with an umbrella having a staff, ribs each comprising an inner section pivotally connected to the staff and an outer section 40 slideable on said inner section, operating means for the latter rib sections including a runner on said staff; a cover of elastic material secured to the staff and to the outer ends of said slideable rib sections, expanding and contracting circumferentially and radially of said frame in the operation of said runner, and being under radial 45 tension along the ribs when the frame is closed, whereby the slideable rib sections are urged inwardly on the inner rib sections in the contracted condition of the covering.

JOHN A. H. SIERS. 60
